W. Peck,

Pump Lift,

No 28,193.

Patented May 8, 1860.

UNITED STATES PATENT OFFICE.

WALTER PECK, OF ROCKFORD, ILLINOIS.

PUMP.

Specification of Letters Patent No. 28,193, dated May 8, 1860.

To all whom it may concern:

Be it known that I, WALTER PECK, of Rockford, county of Winnebago, in the State of Illinois, have invented certain new and useful Improvements in Pumps; and I do hereby declare that the following is a full and exact description thereof, reference being had to the accompanying drawings and to the letters of reference marked thereon.

10 My invention consists in certain improvements of construction in double acting pumps, as hereinafter fully described.

To enable those skilled to make and use my improvements I will describe the mode 15 in which I have practiced the same, referring by letters to the accompanying drawings forming part of this specification and in which—

Figure 1, represents a perspective view of 20 one of my improved pumps. Fig. 2, represents a vertical section through the same. Fig. 3, represents a partial vertical section illustrative (to be explained hereinafter) and Fig. 4, represents detail perspective 25 views of platform collars.

In the drawings the piston of the pump is illustrated as being coupled to the first section of the pipe. This illustration is theoretical, to admit of drawing on a larger scale 30 than could be well adopted were the pump placed at the distance below the platform at which it would be in practice.

In the different figures the same letter indicates the same part of the apparatus.

35 A, represents the platform or floor which covers the well hole and which may be made of any desirable material. On this floor A is erected a cast iron stand, C, in the top of which is hung on a pivot the handle, 40 B, by which the pump is operated.

a, is the hollow piston rod which is connected at its lower end to the piston, T, and has affixed to or formed on its upper end the cap F, which is furnished with a suitable 45 spout D, and which is pivoted by a pin, c, to the short end of the lever or handle B.

O, is a block which is permanently located at the bottom of the well and to which is secured a stand P, so constructed as to form 50 a box for and receive a ball joint h, formed on the lower side of the bottom piece, g, of the pump cylinder: this bottom piece, g, is formed with a series of conduits or induction passages, m, extending from its outer circumference to its center hole, or basin, n, (see Figs. 2 and 1) and is constructed so as

to fit (with a packing x) into and be securely fastened to the bottom of the pump cylinder E, and is furnished with a flap valve, l.

60 The upper end of the pump cylinder is made with an enlargement, or rim of increased diameter as shown at t, (see Figs. 2 and 1) which forms a shoulder on the internal surface of the cylinder. On this shoulder is placed the packing of the piston T, which packing is formed as follows viz:

r, is an annular collar which encircles the piston T, and fitting within the rim portion, t, of the cylinder rests on the shoulder, w, (see Fig. 2). On this collar is placed a layer 70 of fibrous packing material, p, (tinted blue at Fig. 2) and on top of this packing, p, is placed another (packing) ring, or collar, q, onto which latter collar (q) the top cap S 75 comes down.

The hollow piston, T, is considerably less in external diameter than the internal diameter of the cylinder E, and said hollow piston, T, is formed with a head, I, which 80 is of a sufficiently great diameter to fill the cylinder and is furnished with a suitable packing ring, z, to insure its tight working in said cylinder as illustrated at Fig. 2. In the bottom of the piston is located a 85 flap valve, k, opening upward, as does also valve, l, already referred to. It will be seen by reference to Fig. 2 that as the head, I, of the piston T, leaves the upper end of the cylinder E, an annular space G is created 90 in said cylinder and surrounding the body of the piston T. A communication between this space, G, and the inside of the piston T, is formed by conduits, Y, in the head I, of the piston (see Fig. 2.).

95 i is a valve in the upper end of the piston and opening upward.

b is a slot cut in the floor A, equal in width to the diameter of the piston rod, a, and of sufficient length to admit of the 100 throw or swing of said rod, a, the pivot, e, moving in the arc of a circle.

d, is a collar which is fitted loosely to the rod, a, and of sufficient diameter to cover the whole of the slot, b, and slides on top 105 of the floor A while the rod, a, passes up and down through it.

e and f are two collars one with a slot and the other without. The advantage of these collars will be understood by the description of their operation which will be 110 presently given.

It will be seen that by connecting the lower extremity of the pump to the permanent stand by means of a universal joint or "ball and socket" joint as herein described the upper end of the pump rod may be vibrated in any desired direction (that is the stand, *c*, may be arranged on any side) and further that there will be no jump or jar to the pump it being held down perfectly tight and yet allowed to vibrate freely. I am aware that in this kind of pump the cylinder has been hung by a link joint to a weight or anchor: but such an arrangement does not accomplish the ends attained by my improvement.

The pumping operation of my improved apparatus is as follows viz: Suppose the piston head, *I*, to have been elevated until nearly in contact with collar, *w*, (by pulling down the hand end of lever *B*,) when the water will have arisen by atmospheric pressure in the cylinder *E*, until up to bottom of piston head, *I*, passing through the valve, *l*; then by causing the piston to descend the valve, *l*, will be closed and the water contained in the cylinder will be forced to occupy the inside of piston, *T*, passing through valve *k*, and passing the conduits, *y*. The water will also fill round the piston in the annular space, *G*. Then on causing the piston to ascend the body of water in it will close the valve, *k*, and all the water in the space, *G*, will be forced through the conduits, *Y*, into the piston, *T*, and up through valve, *i*. Meanwhile the cylinder is filling up below the piston and immediately on the redescent of the piston the column of water in the cylinder being cut off by closing of valve, *l*, will be forced into the piston raising the column of water above and filling the space, *G*. It will be seen that thus the column of water is elevated at each upward and each downward stroke and also that the column of water is forced out at the exit at each stroke of the piston with a velocity proportionate to the velocity of the stroke.

It will be seen that by the construction of the pump as hereinbefore described it is made double acting with simply a single cylinder, and piston, while the apparatus is simply and durably formed. The bottom piece, *g*, it will be observed is formed with the ball, *h*, for the attachment and also with radiating and nearly horizontal conduits, or induction passages, *m*, leading to its center cavity, *n*, while on its top is arranged the valve, *l*, and around its circumference an inserted packing ring, *x*. By the employment of a separate bottom attached to the cylinder the lower valve may be much more readily fitted to its seat than when arranged in a solid bottom to the cylinder and this separate bottom piece I make constitutes the ball joint also, while by forming said bottom

piece with the annular packing, *x*, I render it capable of being more easily and perfectly fitted to the cylinder (by simply inserting it and securing by bolts) and by forming therein the induction passages *m*. I am enabled to more economically make said passages than if made in the cylinder itself.

In order to avoid the objections to this kind of pump which arise out of the lateral motion of the piston rod (or pipe) in the floor or well cover, without the expense of the necessary mechanism of converting the vibratory motion of the handle into a vertical reciprocating motion to operate said piston rod, I have arranged around the piston rod a collar, *d*, which is so fitted as to admit of the moving of the said rod up and down through it and is of sufficient diameter to extend over the slot, *b*, in floor *A*, at all times during its sliding over the surface of the latter to keep said slot always covered and prevent the falling in of particles of dirt. At Fig. 3, is illustrated another method of protecting the slot, *b*, by means of two collars one (*e*) being formed with slot corresponding in size and shape to the slot in the platform, *A*, the other (*f*) fitted to slide vertically on the rod, *a*, and laterally on the top of the lower one (*e*) and both made with convex tops. This peculiar arrangement of collars *e* and *f*, thus formed is exceedingly advantageous in freezing weather, when the water dripped or spilt on the floor *A*, would freeze the collar *d* (shown at Figs. 1 and 2) tight to said floor and obstruct the ready operation of the apparatus. It will be seen that by the employment of the two collars *e* and *f* arranged as shown, the surface on which the moving collar slides is elevated to a level above that which would probably be reached by flooding the floor *A* and also that both collars being convex any water thrown on them would run off while the surface of contact between the collars is so small as not to afford an opportunity for the formation of sufficient ice to impede the operation of the pump. The operation of the collars and pump is illustrated at Fig. 3, where the moving parts are shown in two different positions one in black the other in red lines.

The perfect packing of the hollow piston *T*, in the pump head is insured by a very simple and novel device consisting of two rings or annular collars *q* and *r*, with a body of fibrous material between and the whole so arranged that by the screwing down of the cap *s*, the body of packing material *p*, (see Fig. 2) shall be forced out around its external circumference against the pump cylinder and around its internal circumference against the piston. It will be seen that by thus combining the body of packing material *p*, with two simple collars (stamped

of sheet metal by machinery and used as an article of manufacture) and the screw cap *s*, a simple and effective packing box is attained.

5 Having described the construction and operation of my improvements, what I claim as of my invention and desire to secure by Letters Patent is—

1. Coupling the lower end of the pump 10 to a fixed stand *P*, or its equivalent, by means of a universal joint substantially as hereinbefore described for the purpose set forth.

2. In combination with the moving rod, or pipe *a*, the stationary collar *e*, and sliding collar *f*, the whole arranged and operating substantially as hereinbefore described for the purpose set forth. 15

In testimony whereof I have hereunto set my hand and affixed my seal this fif- 20
teenth day of March, 1860.
